DESIGN FOR A FOOD WARMER OR SIMILAR ARTICLE

Frederick F. Gunther, Chicago, Ill., assignor to Helmco, Inc., Chicago, Ill., a corporation of Illinois

Application July 31, 1944, Serial No. 114,661

Term of patent 14 years

(Cl. D44—1)

To all whom it may concern:

Be it known that I, Frederick F. Gunther, a citizen of the United States and a resident of the city of Chicago, in the county of Cook and State of Illinois, have invented a new, original, and ornamental Design for a Food Warmer or Similar Article, of which the following is a specification, reference being had to the accompanying drawing, forming a part thereof.

On the drawing:

Figure 1 illustrates a side elevational view of the food warmer or similar article, showing my design;

I claim:

The ornamental design for a food warmer or similar article, as shown.

FREDERICK F. GUNTHER.
